UNITED STATES PATENT OFFICE.

GOTTLOB P. THUMM, OF LOWELL, MASSACHUSETTS.

BEER-CARBONATING DEVICE.

1,100,036.

Specification of Letters Patent. Patented June 16, 1914.

Application filed November 6, 1913. Serial No. 799,506.

To all whom it may concern:

Be it known that I, GOTTLB P. THUMM, a citizen of the United States, residing at Lowell, in the county of Middlesex and 5 State of Massachusetts, have invented certain new and useful Improvements in Beer-Carbonating Devices, of which the following is a specification.

This invention relates to apparatus for 10 charging liquids with gas and particularly for charging beer and ale with carbonic acid gas.

It is especially useful in the manufacture 15 of beer or ale at the brewery but may be used in other connections if desired.

With my device, the gas and beer are rapidly and thoroughly mixed, while the whole apparatus is easily cleaned.

My device can be made of aluminum which 20 does not corrode, and it is of such character that there is little danger that it will be broken.

In the drawings, Figure 1 is an elevation of the principal feature of my device as it is 25 passed through the wall of a carbonating tank at the brewery. Fig. 2 is a sectional elevation similar to Fig. 1. Fig. 3 is a section on line X—Y of Fig. 1 looking from the right. Fig. 4 is a side elevation of a 30 beer tank of the horizontal type with my device in place with necessary connections and attachments. Fig. 6 is a view of the outlet end of the mixing tube. Fig. 5 is a detail in sectional elevation showing my device attached to a wooden beer tank.

My device comprises a gas injector nozzle A which has a tapering snout 10 and a base 11. Carried by nozzle A and preferably attached thereto by screw threads is a mixing 40 tube holder B. This comprises a head 24 and a neck 20 threaded on the inside to engage outside threads on nozzle A as shown in Fig. 2. The head 24 of holder B is cylindrical and hollow and is provided around 45 the outside with openings 21 and preferably at the end with other openings 22 for the intake of the beer.

The mixing tube C is threaded on the outside at one end to engage interior threads 50 in the head 24 of holder B whereby it can be readily unscrewed and removed for cleaning purposes. This mixing tube C is preferably several times larger in diameter than the snout of nozzle A and is of such length 55 that its end will extend to about the middle part of the beer mixing tank. Nozzle A may

be attached in various ways to a valve such as P which passes through the wall D of the beer mixing tank. As shown in Figs. 1 and 2, the body of valve P may be screwed through wall D and the base 11 of nozzle A may be screwed up tightly against a nut 12 which is screwed tightly up against wall D. A wrench may be applied to nut 12, so that wall D may be tightly gripped between it 35 and a flange 34 on the outside of valve P.

Valve P may be of any suitable design whereby it may be opened or closed from the outside, but I prefer the golden gate design wherein passages 35 may be opened or 70 closed by means of wings 36 carried by a stem 37 the end 38 of which is of polygonal form adapted to fit into the end of tubular key 30. Key 30 is tubular with one end shaped to fit end 38 and the other end 39 75 adapted to fit into an elastic gas tube 33 preferably of rubber. It has studs 49 which engage slots inside flange 34 and passages which connect with the interior of valve P and thus with passages 35. A handle 43 80 permits key 30 to be turned at will.

In Fig. 4 is shown a horizontal beer mixing tank H with a domed wall K through which passes the valve P to which on the inside is screwed the nozzle A carrying the 85 holder B and mixing tube C which extends well into the tank. Nozzle A is preferably bent to bring tube C to a horizontal position. By means of any suitable detachable coupling or key 30, the valve P can be opened or 90 closed and the nozzle A can thus be disconnected with the outside or connected through key 30 attached to a rubber gas tube 33, with a metal gas tube 31 having suitable valves 32 coming from a source of gas supply which 95 it is not necessary to show. When the gas is turned into the nozzle A, it will be readily seen that an injector action is set up whereby as the gas rushes through mixing tube C, it carries the adjoining beer in through inlets 21 and 22, and the gas and beer are mixed as they pass through tube C and discharge from the outlet 13 thereof into the other beer in the tank. In this manner a 100 general circulation, creation of currents and a general mixing of the beer and gas is produced in the tank whereby the beer is rapidly saturated. I prefer to use a relief valve M on the tank whereby if the pressure exceeds a certain point, the valve will be opened and the excess of pressure discharged. I prefer 110 to use a gage 50 in connection therewith, by

which the desired pressure may be set. It is preferable to set the relief valve for a lower pressure than that of the gas in the inlet pipe 31 as the pressure is reduced in 5 passing through the beer.

In Figs. 4 and 6, I show a preferred construction of the mixing tube wherein I pass into the outlet end of mixing tube C, a spirally twisted strip of metal T which fits 10 longitudinally loosely inside therein and is held in place by means of a pin 45 which passes through C and T near the outlet thereof. The effect of this spiral is to divide the gas and beer in mixing tube C and 15 cause them to travel around spirally in two separate channels whereby they are better mixed, and when they are discharged from the outlet end of the mixing tube, they still maintain somewhat of a rotary motion and 20 are thereafter better mixed. This spiral strip also counteracts the tendency of the gas delivered from nozzle A to rise and to travel along the upper part of mixing tube C.

In Fig. 5, I show the manner in which the golden gate valve P may be screwed into 25 and through the wooden wall 46 of a beer tank W. The threads on the base of nozzle A are cut to correspond with the threads on 30 valve P.

Which ever form of valve is used, it should pass through the wall of the beer mixing tank and should be operative from

the outside where it is also connected with a gas supply tube. It may or may not be removable with the gas supply tube.

I claim:

1. In a carbonating device for beer, the combination of a mixing tank, and a gas supply tube with a valve operative from the outside connected with such tube and which extends through the wall of the tank, an injector nozzle attached inside the tank to the valve, a mixing tube holder having inlets and carried by the nozzle, and a mixing tube surrounding the end of the nozzle carried by the mixing tube holder as described.

2. In a carbonating device for beer, the combination of a mixing tank, and a gas supply tube, with a valve operative from the outside connected with such tube and which extends through the wall of the tank, an injector nozzle attached inside the tank to the valve, a mixing tube holder having inlets and carried by the nozzle, a mixing tube surrounding the end of the nozzle carried by the mixing tube holder, and a spiral strip of metal which fits longitudinally inside the mixing tube as described.

In testimony whereof I hereto affix my signature in presence of two witnesses.

GOTTLOB P. THUMM.
